UNITED STATES PATENT OFFICE.

FRANK S. CROWELL, OF TOLEDO, OHIO, ASSIGNOR TO THE EDWARD N. RIDDLE CO.,
OF TOLEDO, OHIO, A CORPORATION OF OHIO.

DESIGN FOR A BRACKET PLATE FOR LIGHTING FIXTURES.

Application filed August 22, 1924. Serial No. 10,532. Term of patent 7 years.

To all whom it may concern:

Be it known that I, FRANK S. CROWELL, a citizen of the United States, and residing at Toledo, in the county of Lucas and State of Ohio, have invented a new, original, and ornamental Design for a Bracket Plate for Lighting Fixtures, of which the following is a specification, reference being had to

the accompanying drawing, forming part thereof.

Fig. 1 is a side view.

Fig. 2 is a front view.

I claim:

The ornamental design for a bracket plate for lighting fixtures as shown

FRANK S. CROWELL.
